UNITED STATES PATENT OFFICE.

MAX AUERBACH, OF BERLIN, GERMANY.

AUTOMATIC SHUTTLE-CHANGING MECHANISM FOR LOOMS.

Specification of Letters Patent. Patented July 25, 1916.

1,192,261.

Application filed January 23, 1914, Serial No. 813,967. Renewed March 25, 1916. Serial No. 86,783.

To all whom it may concern:

Be it known that I, MAX AUERBACH, a subject of the German Emperor, residing at Potsdamerstrasse 20, Berlin, Germany, have 5 invented certain new and useful Improvements in Automatic Shuttle-Changing Mechanism for Looms; and I do hereby declare the following to be a full, clear, and exact description of the invention, such as will 10 enable others skilled in the art to which it appertains to make and use the same.

This invention relates to an automatic shuttle changing mechanism for looms by means of which the ejection of the shuttle carrying the used spool and the introduction 15 into the shuttle box for a shuttle carrying a new spool are effected in two phases or operations.

Primarily the invention consists of a shuttle box, having a pivoted rear wall, adapted 20 to swing outwardly against spring tension, and a vertically sliding front wall, in combination with a shuttle magazine, and means coöperating between said shuttle box and 25 magazine, to cause said front wall to be raised and a full shuttle to be forced into said shuttle box, by the outward swing of said rear wall, in ejecting an empty shuttle, and the forward movement of the shuttle 30 box.

The subject matter of the invention is illustrated diagrammatically according to one method of carrying the same into effect, in the drawing accompanying the present 35 specification.

Figure 1 is a side elevation with a portion in section; Fig. 2 is a plan, the outlet inclined guide 2 and the container 3 being omitted; Fig. 3 shows the arrangement of 40 the shuttle changing mechanism with respect to the framework of the machine, partly in elevation and partly in section.

In the method of carrying out the invention shown in the drawing 1 is a shuttle box, 45 provided at one end with an inclined outlet guide 2 for the passage of the shuttle carrying the empty spool. This outlet guide 2 projects into a holder or container 3. The shuttle box is provided with a wall or partition 5 at the back, which turns around a vertical pivot 4. The wall or partition 5 is provided with a springy projecting surface 6 in order to cushion or buffer the shuttle thrown into the shuttle box. The pivoted 50 partition 5 is kept pulled inward by the action of a tension spring 7 so that its front edge tends to press against the wall 8 of the shuttle box. In this position of the parts, a shuttle entering the shuttle box is caught by the partition and conducted sidewise and 60 outward so that it passes through the inclined outlet guide 2 into the container 3. The retention or fixing of the pivoted partition 5 in its position parallel to the front wall in which the shuttle passes into the 65 shuttle box, is effected by a suitably controlled stop 9. After this first operation or phase of the ejection, namely the removal of the shuttle carrying the empty spool, has taken place the introduction of a new shuttle 70 carrying a full spool is effected in the following manner:—At the rear end of the pivoted partition 5 of the box is a pivot 10, which is connected by means of a link 11 to a two armed lever 12 turning about a vertical pivot. One arm of this two armed lever 12 presses against the arm 13 of a pivoted bell-cranked lever turning about horizontal bearings 14. 15 is the horizontal arm of this bell-crank lever and it is adapted to support 75 a link rod 16 having a projecting nose 17 which rests thereon. The link rod 16 is provided with a hook-like projection 18 which in the normal position of the pivoted partition 5 of the shuttle box, is at a lower 80 level than the fixed projection 19 on the shuttle box 1 so that it can pass freely. When, however, the link rod 16 is raised by the arm 15 of the bell-crank lever in the fixed position of the wall 5 of the shuttle 85 box, upon the forward movement the projection 19 engages the projection 18 and the link rod 16 is carried along. This causes the two-armed lever working on pivots 20 to be turned so that the upper arms 21 act upon the rods of slides 23 controlled by springs 22. The slides 23 being pushed forward 90 pass into a recess in the shuttle magazine 24, pushing out the lowermost full shuttle 25, in the direction of the arrow, it being understood that rods or projecting members 23a extend rearwardly from the tops of the slides 23 to support the upper shuttles in the magazine, during the forward and return 95 movement of the slides, as the lowermost shuttle is forced into the shuttle box. The shuttle comes against the pivotally mounted plate 26, located between the cheeks of the shuttle box 1, at the end thereof. 27 are 100 noses or projections on the plate 26 which 110

engage under projections 28 provided on the forward partition 8, which slides in guides 29 in the moving parts. The swinging over of the plate 26 therefore raises the forward partition 8, so that the shuttle 25, pushed forward by slides 23 passes into the space in the shuttle box 1 between the front partition 8 and the rear partition 5, in other words it comes into the forward end position 10 in the shuttle box. The latter has itself moved in the meantime so that it is close to the shuttle magazine 24. Suitable recesses 30 are provided in the pivoted flap 26 into which the correspondingly formed slides 23 15 can pass freely in case there are no more shuttles in the shuttle magazine 24 to be pushed out by its movement.

What I claim as my invention and desire to secure by Letters Patent of the United 20 States of America is:—

1. In an automatic shuttle changing mechanism for looms the combination of a shuttle box; a spring controlled rear wall pivoted thereto, providing for the ejection of an empty shuttle; a vertically sliding front wall for said shuttle box; a swinging plate mounted forwardly of said sliding front wall; a shuttle magazine; means coöperating between said magazine and shuttle 25 box, for feeding a full shuttle to said shuttle box, upon the operation of said pivoted wall and the forward movement of said shuttle box; and means coöperating between said swinging plate and said sliding front 30 wall for raising the latter, as said full shuttle is advanced into engagement with and past said swinging plate, to admit of the passage of said full shuttle into operative position in said shuttle box, substantially as 35 described.

2. In an automatic shuttle changing mechanism for looms, the combination of a shuttle box; a spring controlled rear wall pivoted thereto, providing for the ejection of an empty shuttle; a vertically sliding front wall for said shuttle box, having a forwardly projecting member; a swinging plate mounted forwardly of said sliding wall, having a rearwardly projecting member, engaging beneath the member on said sliding wall; a shuttle magazine; and means coöperating between said magazine and shuttle box, for feeding a full shuttle to said shuttle box, upon the operation of said pivoted wall and the forward movement of said shuttle box, said swinging plate being disposed in the path of travel of the advancing full shuttle, and the inward swing of said swinging plate causing said sliding front wall to rise, to admit of the passage of said full shuttle into oper- 60

ative position in said shuttle box, substantially as described.

3. In automatic shuttle changing mechanism for looms, the combination of a shuttle box; a spring controlled rear wall pivoted thereto; a vertically movable front wall for said shuttle box; a shuttle magazine; a slide member adapted to engage the lowermost shuttle in said magazine and feed same forward into said shuttle box; a lever engaging said slide for operating the latter; a longitudinally movable rod pivotally connected at one end to said lever, said rod having a projection thereon and being adapted to swing in a vertical plane; a projection on said shuttle box adapted to engage the projection on said rod, when the latter is swung upwardly; means disposed between said pivoted wall and said rod for elevating the latter, when said pivoted wall is swung outwardly for ejecting an empty shuttle; and means for elevating said front wall upon the advancement of a full shuttle, to admit of the passage of said full shuttle into operative position in said shuttle box, substantially as described.

4. In automatic shuttle changing mechanism for looms, the combination of a shuttle box; a spring controlled rear wall pivoted thereto; a vertically sliding front wall for said shuttle box; a swinging plate pivotally mounted forwardly of said sliding wall; co-operating projections carried by said swinging plate and sliding wall to elevate the latter upon the inward swing of said swinging plate; a shuttle magazine; a slide member adapted to engage the lowermost shuttle in said magazine and feed same forward into said shuttle box, said sliding plate being disposed in the path of travel of said advancing shuttle; a lever engaging said slide for advancing the latter; a longitudinally movable rod pivotally connected at one end to said lever, said rod having a projection thereon and being adapted to swing in a vertical plane; a projection on said shuttle box adapted to engage the projection on said rod, when the latter is swung upwardly and the shuttle box moves forwardly; and a system of levers disposed between said pivoted rear wall and said rod for elevating the latter when said pivoted wall is swung outwardly for ejecting an empty shuttle, substantially as described.

In testimony whereof, I affix my signature, in presence of two witnesses.

MAX AUERBACH.
